UNITED STATES PATENT OFFICE.

WILLIAM W. UHLINGER, OF NEW YORK, N. Y.

HARNESS-EVENING MECHANISM FOR LOOMS.

SPECIFICATION forming part of Letters Patent No. 629,220, dated July 18, 1899.

Application filed May 4, 1897. Serial No. 635,063. (No model.)

To all whom it may concern:

Be it known that I, WILLIAM W. UHLINGER, of New York, in the county of New York and State of New York, have invented certain new and useful Improvements in Harness-Evening Mechanism for Looms; and I do hereby declare the following to be a full, clear, and exact description of the invention, such as will enable others skilled in the art to which it appertains to make and use the same.

This invention relates to looms, and particularly that class known as "double-lift open-shed dobbies;" and it consists, essentially, of a machine of the character specified that is operated by a one-card cylinder, including devices for actuating the harness-shafts.

The invention consists in the details of construction and the arrangement of the several parts, which will be more fully hereinafter described and claimed.

The object of the invention is to produce a loom of the double-lift open-shed dobby type, on which is adapted to be employed any set of pattern-cards that are used on single machines of this character with the same weaving effect, of course providing that the index, number of needles, &c., are the same.

Particular attention is directed to the following description, which will set forth the use of inverted hooks or hooks turned upside down reversely to the ordinary arrangement, and also a single-card cylinder, which operates the pattern-cards on a double-lift open-shed dobby, and also mechanism for leveling or letting down the hooks, so as to level the harness-shafts.

In the accompanying drawings, Figure 1 is an elevation showing the improved attachments and so much of the loom as to illustrate the application of the invention. Fig. 2 is a detail view showing the mechanism, including the hooks and parts connected thereto. Fig. 3 is a detail view of the leveling mechanism for the harness-shafts.

Referring to the drawings, wherein similar numerals of reference are employed to indicate corresponding parts in the several views, the numerals 1 1 designate the side pieces of the frame, which form the bearings or supports for the mechanism hereinafter described. These bearings and supports may be of the most approved pattern, and jour-

naled in those carried by the said side pieces and extending between the latter is a rock-shaft 2, having two arms 3 extending beyond 55 opposite sides of the shaft and forming a double lever. Attached to the said shaft 2 is an operating-lever 4, having a slot 5 in its outer end for connection thereto of an operating device or mechanism. The ends of the arms 60 3 are connected up to plunger-rods 6 and 7 by means of links 8, the said plunger-rods having laterally-projecting pins, to which the links are pivoted. To the ends of the plunger-rods 6 and 7 knives 9 are attached, adapted to be engaged by hooks 10, which are pivoted to the ends of the jack-levers 11, which are centrally pivoted to harness-levers 12. The upper series of hooks 10 rest upon the bent ends 13 of rods 14, extending downwardly through the lower series of hooks, as clearly shown in Fig. 2, the lower ends of said rods 14 being engaged by indicator-levers 16, pivotally mounted on a cross bar or shaft 17 and operated upon by the needles. 75 The rods are stepped in recesses therefor in the indicator-levers, as shown, and said levers are extended to engage the lower hooks.

A bell-crank lever 18 is movably secured to one of the side pieces 1 of the frame and is 80 connected by a rod 19 to one arm of a second bell-crank lever 20, the other arm of the bell-crank lever 18 having a depending rod 21 pivoted thereto, which is connected at its lower end to a card-cylinder 22, the pattern-85 needles 23 being mounted in a guide 23'. Adjoining the cylinder 22 is a depending pivoted hook 24, having a rounded shoulder in one edge thereof, as at 24', and a helical spring 25, connected to the lower end thereof and 90 also to an adjacent part of the frame, this hook serving to turn the cylinder by engaging lugs or rounded portions 26 at the corners thereof, thereby presenting to the needles another one of the pattern-cards carried 95 by the said cylinder. The harness-levers 12 are movably connected to a transverse shaft 27 at the top of the supporting-frame, and each is provided with a depending arm 28, connected to the harness-frame by a cord or 100 flexible connection 29, that passes over a sheave-wheel 30, the connection being made by a loop 31, that engages one of a series of notches or recesses 32 at the inner side of the

said arm. In connection with the jack-levers 11, that are pivoted to the harness-levers 12, are cross-bars 33 and 34, extending between the side pieces of the frame and forming stops 5 for the said jack-levers. The device for releasing the hooks consists of a shaft 35, located and suitably supported at one side of the machine. This shaft is provided with a spirally-arranged projection or fin 37. The 10 said projection 37 engages the hooks and moves them out of contact with the knives. The shaft 35 is operated by a lever 36, having a counterbalancing-weight 38. It should be understood that when the hooks are disengaged they will be returned to their normal positions through the intervention of the levers 12 and weighted flexible connections which pass over the sheave-wheel. The 15 weight of harness and weights on the bottom 20 of the hooks serve to return the hooks to their normal positions after they have been forced off from the knives by the spiral projection 37. The lever 36, which operates the shaft 35 to disengage the hooks, is limited in its 25 movement in both directions by a suitable lug or projection 39, as shown in Fig. 1, which is adapted to engage with shoulders or stops 40 on an adjoining bracket at the end of upper plunger-rod 6.

30 In the operation of the machine the movement of the lever 4 will cause an opposite reciprocation of the upper and lower hooks through the intervention of the plunger-rods connected to the arms 3 by the links 8, and 35 thereby carry the knives that engage the hooks and push them forwardly, the said lever 4 being operated by well-known mechanism, as clearly shown in patent granted to W. P. Uhlinger, dated May 21, 1889, No. 403,565. The card-cylinder is elevated and 40 lowered at every rotation of the crank-shaft and beat of the lay and is driven by an eccentric or crank from the main shaft of the loom, which is connected to the end of the bell-crank lever 20, motion being imparted 45 through the rod 19 to the bell-crank lever 18 and thence by the depending rod 21 to the said cylinder. The vertical reciprocation of the cylinder through the contact of the lugs 50 or projections 26 thereof with the shoulder of the depending hook 24 turns said cylinder to bring successive cards in position. On the

upward movement of the card-cylinder the needle 23 will engage the indicator-lever 16, provided a blank space of the card is under 55 the same. If an opening in the card is presented to the needle, the latter will not be operated upon, but remain in the position shown in Fig. 1. When the blank space comes under the needle, the indicator-lever 60 65 65 is pressed upon in each instance and the rod 14 is let down, as also the end of the indicator-lever. Of course when the said indicator-lever is operated or raised by the needle the hooks are relieved and drop by gravity, and the knife in its outward course does not engage the hook, and consequently the harness-shaft which is operated remains in the lowered position. By the inverted arrangement of the hooks a great advantage is 70 secured. In ordinary card-dobbies the hooks are in reverse positions to those shown in the drawings and must be held up when the cylinder operates, and the needles must lift the hooks off the knives. By pulling the hooks 75 through the mechanism set forth jack-levers are actuated, and if both hooks are pulled alternately the harness-shaft will stay up, and if after one pick the hooks are engaged they will rise, and if after the next pick the 80 hooks are not engaged the harness-shaft will stay down.

Having thus described the invention, what is claimed as new is—

In a loom, the combination of a pair of plungers carrying knives, upper and lower hooks having the shouldered portions thereof uppermost, a card-cylinder and mechanism for synchronously operating the several parts, an outer shaft located in the range of the plunger having a projection thereon arranged in a spiral line adapted to engage the ends of the upper set of hooks and provided with a counterbalancing-weight, and an operating-lever attached to said shaft, substantially as 95 described.

In testimony whereof I have signed this specification in the presence of two subscribing witnesses.

WILLIAM W. UHLINGER.
